UNITED STATES PATENT OFFICE.

NILS H. ANDERSON, OF EAST HAMPTON, CONNECTICUT, ASSIGNOR TO THE NOISELESS TYPEWRITER COMPANY, OF MIDDLETON, CONNECTICUT, A CORPORATION OF CONNECTICUT.

INTERMITTENT-GRIP DEVICE.

1,242,119.

Specification of Letters Patent.

Patented Oct. 9, 1917.

Original application filed April 27, 1910, Serial No. 557,925. Divided and this application filed April 23, 1915. Serial No. 23,317.

To all whom it may concern:

Be it known that I, NILS H. ANDERSON, a citizen of the United States, residing in the town of East Hampton, in the county of Middlesex and State of Connecticut, have invented certain new and useful Improvements in Intermittent-Grip Devices, of which the following is a full, clear, and exact description, such as will enable others skilled in the art to which it appertains to make and use the same.

My present invention relates to a ribbon driving mechanism for typewriting machines, and especially to the spring drum and associated parts provided for driving the carriage and actuating the ribbon mechanism.

This application is a division of my parallel pending application, Serial No. 557,925, filed April 27, 1910.

The objects of the present invention are to provide simple and efficient mechanism of the above character which will be cheap to manufacture; but its further and especial object is to provide means for driving the ribbon which will be substantially silent in its action and have free and easy movement.

In the accompanying drawings, wherein is shown one of many possible embodiments of my invention,

Figure 1 is a side elevation, partly in section and broken away, of a portion of a typewriting machine sufficient to illustrate one embodiment thereof;

Fig. 2 is a plan view, partly in section, taken substantially on the line $x-x$, Fig. 1;

Fig. 3 is a side elevation looking to the right from the line $y-y$, Fig. 2, with the shaft in section;

Fig. 4 is a sectional detail view taken on the line $z-z$, Fig. 2;

Figs. 5 and 6 are detail views of different clutch members.

Similar reference characters refer to similar parts throughout the several views of the drawings.

While the present invention is herein illustrated and described with reference to that form of typewriter known as the noiseless typewriting machine, it is to be understood, however, that the entire mechanism, as well as certain individual features thereof, may be applied to other forms of machines as well.

Referring to these drawings in detail, 1 55 represents one of the side plates of a typewriting machine, between and from which is supported a horizontal bar or beam 2 which in turn supports a U-shaped bearing member 3 resting thereon between upwardly projecting flanges 4 and secured thereto by means of a nut or screw 5, adapted to support the main driven shaft 6 carrying a driving drum 7. One end of this shaft 6 is provided with a beveled gear 8 65 meshing with a second beveled gear 9 on a transverse shaft 9' which, through suitable gears 10, drives ribbon spool spindles 10' at opposite sides of the machine (only one being herein shown), which are operatively 70 connected at their upper ends with the ribbon spools for feeding the ribbon past the printing point, in a well known manner. One or more of these gears, 10 for example, is preferably stamped from sheet metal, 75 thereby materially decreasing the cost of manufacture of these parts.

The ribbon driving drum 7 is provided at one point on its periphery with an upwardly extending lug 11, Fig. 3, preferably being 80 an upwardly punched integral part thereof, to which one end of a tape 12 is secured, the opposite end being connected to a pin or stud 13 on a carriage frame 14, which is adapted to reciprocate on a shift rail 15. 85 Punched inwardly from the inner periphery of the spring drum is another lug 16 similar to the lug 11 to which one end of a spiral spring 17 is secured. The opposite end of this spring, after making a plurality 90 of convolutions in the usual manner about the interior of the drum, is secured to a relatively stationary hub 18 about the driven shaft 6. For the sake of clearness the body portion of the spring 17 has been omitted 95 from the drawings, merely the end portions thereof being shown in Figs. 2 and 3. This drum 7 comprises a cup-shaped sheet metal container having a cover plate 19 to which parts are secured, respectively, bearing 100 plates 20 and 21. Screws 22, engaging tapped-out studs 23 located at a plurality of points about the interior of the drum, hold the cover in place. The bearing plate 20 is loosely mounted upon the driven shaft 6 105 and abuts one end of the hub 18, which is hollowed out to substantially its entire length to form a bearing for the end of the

driven shaft 6. The greater portion of the bearing for this shaft in the hub is slightly enlarged, thereby lessening the friction when one of these parts is turned relatively 5 to the other, the extreme end of the recess only being of proper size to form a close-fitting bearing, as shown by the dotted lines in Fig. 2. The bearing plate 20 and driven shaft 6 normally rotate in the same direction 10 when the carriage is moving in a letter-spacing direction. The bearing plate 21, however, rotates relatively to the stationary hub 18, which it surrounds, and in order to avoid friction between the plate 21 and the hub, ball bearings 24 are interposed to reduce 15 the friction as much as possible when the carriage is moving from right to left. When the carriage is being returned to the beginning of a line the drum 7 turns relatively 20 to the shaft 6, but as this motion is manual, more or less friction is immaterial, the object of the construction being to provide an easy running carriage when moving for letter spacing.

25 The tension of the spring 17 within the drum may be decreased by means of the ratchet mechanism, shown in Fig. 4; the hub 18 is provided with a flattened or irregular portion 25, on which is mounted a ratchet 30 wheel 26 turning therewith. Depending from the U-shaped bearing support 3 is an arm 27 having pivotally mounted thereon an escapement or double armed pawl 28, one arm of which is always adapted to engage 35 the ratchet teeth of the wheel 26 to prevent the same from rotating more than one space at a time under the action of the tensioned spring 17. When oscillated by a handle 29 one arm of the escapement 28 and then the 40 other thereof alternately engages with the ratchet wheel 26 to permit the spring to unwind, step by step. On the other hand, should it be desired to increase the tension of the spring, a screw driver is inserted in 45 a slot 30 at the end of the hub 18 at the rear of the machine and turned to rotate the hub in a clockwise direction, the arms of the pawl 28 slipping over the teeth and holding the same against reverse movement.

50 A threaded bushing 31 is adjustably mounted in one end of the supporting member 3, which engages the shoulders adjacent the flattened portion 25 of the hub 18 for the purpose of taking up the end-thrust of the entire mechanism; the set screw 32 holds it in adjusted position.

55 The spring drum 7 is operatively connected with the driving shaft 6 by means of a plurality of friction clutch members 33 pivotally mounted at 34 on the drum 7. These clutch members are in the form of bell crank levers, the ends 35 of which are curved eccentrically, and coact with the sleeve 36 rigidly secured to the driven shaft 6 by means of a set screw 37. The opposite

ends 38 of the clutch members are engaged by a spring 39 normally tending to urge them outward and force the ends 35 into frictional contact with the sleeve 36. It is thus seen that as the drum rotates to letter space the carriage, these clutch members will be moved into engagement with the sleeve 36, thereby to rotate the driven shaft 6 and feed the ribbon in the proper direction as the carriage moves from right to left. 70

In order to prevent the ribbon from being fed in a reverse direction when the carriage is returned to the beginning of a line, and to aid in removing the clutch members 33 from clutched engagement with the sleeve 36, there is provided a clutch member 40 pivoted at 41 on the bearing support 3, and provided with a curved eccentric face 75 engaging the sleeve 36. About the pivot pin 41 is wound a spring 42, one end engaging the clutch member 40 and the other the bearing member 3, tending normally to urge the clutch member into operative relation with the sleeve 36 on the driven shaft. This clutch member 40, by the contact of its 80 curved face with the sleeve 36, prevents the rotation of the shaft 6, when the carriage is returned to a line-commencing position.

The operation of this device is as follows: The carriage 14 is fed in a letter spacing 95 direction along the shift rail 15 (see Fig. 1) by means of the spring 17 within the drum 7. As the drum rotates to feed the carriage the clutch members 33 grip the sleeve 36, operatively connecting the drum and the 100 driven shaft to rotate the ribbon spool spindle and feed the ribbon. As soon, however, as the carriage reaches the end of the line and the operator starts to return the same to normal position, the clutch member 40 105 will coact with the sleeve 36 to grip and hold the same against a backward rotation, permitting the clutch members 33 to be forced out of engagement with the opposite end of the sleeve 36. In this manner the 110 carriage returns to normal position and re-winds the spring within the drum, whereupon the device is ready to repeat the operation. Should it be desired to regulate the tension of the spring the handle 29 of the 115 escapement pawl may be oscillated, allowing the arms 28 alternately to slip out of engagement with the ratchet 26 carried on the hub 18, which permits the spring to unwind step by step, while if it should be 120 desired to increase the tension of the spring a screw driver is inserted in the slot 30 and the hub rotated to the desired amount, as above described.

It is thus seen that this construction provides for a simple and practical device 125 adapted to operate substantially silently, thereby avoiding the disagreeable clicking heretofore a familiar sound when moving the carriage. The various parts of the 130

mechanism are so arranged and proportioned as to rotate or move in the same direction when operating, or are provided with means whereby the friction between the normally coacting parts is greatly relieved when rotating relatively to each other. By forming parts of this mechanism from sheet metal a strong and efficient but cheap device is obtained. It is thus seen that this invention accomplishes, among others, all of the objects and advantages herein set forth.

Having described my invention, what I claim as new and desire to secure by Letters Patent is:—

1. In mechanism of the character described, in combination, a bearing member, a driving shaft supported thereby, a spring driving drum coaxially supported on said shaft, a spring pressed pawl pivoted on said drum and adapted to frictionally clutch said shaft upon rotation of said driving drum in one direction, and a spring pressed pawl pivoted on said member and adapted to frictionally clutch said shaft upon rotation of said driving drum in the other direction.
2. In mechanism of the character described, in combination, a substantially U-shaped bearing member, a driving shaft supported by said member adjacent its open end, a spring driving drum coaxially supported on said shaft and partially disposed within the opening of said member, means carried by said drum to frictionally clutch

said shaft on rotation of said drum in one direction, and means carried by said member to frictionally clutch said shaft on rotation of said drum in the other direction.

3. In mechanism of the character described, in combination, a substantially U-shaped bearing member, a driven shaft supported by said member adjacent the open end thereof, a spring driving drum coaxially supported on said shaft and partially disposed within the opening of said member, a spacing sleeve fixed on said shaft intermediate said drum and one bearing of said shaft on said member, and clutching means to insure rotation of said shaft upon rotation of said drum in one direction and to permit rest of said shaft upon rotation of said drum in the other direction.

4. In mechanism of the character described, in combination, a driven shaft, a driving drum loosely mounted on said shaft, a sleeve about said shaft, a plurality of pivotally mounted members coacting with said sleeve to form a silent clutch for driving the shaft when the drum rotates in one direction, and spring means normally tending to force said clutch members into operative relation with said sleeve.

In testimony whereof I affix my signature, in the presence of two witnesses.

NILS H. ANDERSON.
